SPREADERS FOR CIRCULAR SAW WOOD
CUTTING MACHINES

Charles Galanga, Maspeth, N. Y.

Application March 28, 1949, Serial No. 83,858

6 Claims. (Cl. 143—157)

1

This invention relates to spreaders for slotted planks or the like.

The object of the invention is to provide a spreader which may be readily placed in operative position, and which is simple in construction, and which efficiently carries out its objective, and which, when not desired to be used, may be readily transposed to inoperative position below the table top to enable the cutter to be used for other purposes than slitting.

In the slitting of wooden planks by a circular saw, the slitted portion has a tendency to bite the saw and the friction causes the slitted end to jump up often injuring the attendant. However, the improved spreader avoids this action of the board or plank, and by exerting a spreading action in the cut slit at the same time facilitates the sawing action.

The invention comprises a member secured to the frame of the machine having a slotted portion, a crescent shaped spreader adapted to have its rear part engage said slot when in operative position, and having its front part adapted to engage the slit in the board or plank formed by the saw at a position adjacent the saw, a pivoting means for the spreader to enable the spreader to be swung from said operative position to its inoperative position out of the path of the board or plank, and a spring for exerting a holding pressure on the spreader when in said slot. More particularly, in the embodiment shown, the spreader is made with a sleeve surrounding a bolt secured to the frame of the machine, with said spring acting upon the sleeve, and with means for adjusting the spring, the bolt acting as a pivot for the movement of the spreader from its inoperative to operative position and vice versa.

The invention will be more fully described hereinafter, embodiments thereof shown in the drawings, and the invention will be finally pointed out in the claims.

In the accompanying drawings,

Fig. 1 is a perspective view of a known circular saw wood cutting machine, with the improvement embodied therein;

Fig. 2 is a perspective view of the improvement showing the spreader in operative position;

Fig. 3 is a perspective view of the improvement showing the spreader in inoperative position;

Fig. 4 is a horizontal section taken on line 4—4 of Fig. 3; and

Fig. 5 is a horizontal section taken on line 5—5 of Fig. 2.

2

Similar characters of reference indicate corresponding parts throughout the various views.

Referring to the drawings, the known saw table 10 having standards or frame 11 and a base 12, shown without the usual and known appurtenances, as driving wheels, etc., supports a circular saw 15.

To a part 16 of the frame 11 there is attached an angular supporting member 17 secured by bolts 18. This member 17 has a plurality of parallel ridges 19 and 19a forming a space or slot 20. The outer ridge 19 is preferably provided with an inclined surface 19a. The member 17 is close against the frame as at 21.

Spaced from the ridges 19 is a horizontal bolt 22 extending through an opening 23 of a vertical part 16a of the frame, and the bolt 22 has a bolt head 24 and an adjustable nut 25 on the screwthreaded end 26 of the bolt 22. An angular spreader member 30 has a sleeve 31 surrounding the bolt 22 with its inner portion 32 resting on the frame 16a (when in off position, Figs. 3 and 4), and with its outer portion 33 spaced from the bolt head 24. A spiral spring 35 is interposed between the bolt head 24 and this outer portion 33 of the sleeve 31. The sleeve 31 is preferably formed by looping the end of the plate 36. The plate 36 is bent at right angles at 37, and then extends in partial crescent shape to form the spreader or slitter proper 38. The edge 39 is bevelled to facilitate its entrance in the slit in the wood formed by the saw cutting.

The spreader or slitter proper 38 is placed in operative position (Figs. 2 and 5) by inserting it into the slot of the sawn wood or plank, whereby the part 36 is raised, and the sleeve 31 is raised accordingly away from the part 16a of the frame, and the spring 35 is subjected to compression, which presses the spreader proper 38 with considerable force into the slot 20, so as to hold tightly in the slot 20 to prevent the spreader proper 38 from being disengaged therefrom by any tugging of the wood planks during the sawing action.

The bevelled portion 19a of the outer ridge 19 facilitates the entrance of the spreader proper 38 into the slot 20. The spring 35 may be adjusted by the rotation of the bolt nut 25. The plank or board 40 of wood is shown in phantom fashion in Fig. 1, with the saw 15 cutting the slit 42, and the spreader proper 38 within the slit 42, the arrow 43 (Figs. 1 and 2) showing the direction of movement of the wood board or plank 40.

When it is not necessary to use the spreader, the spreader proper 38 is raised and moved by a turning action around the pivot bolt 22 into in-

55

active position, as shown in Fig. 3. The spreader or slitter proper is then entirely concealed below the table 10 and is out of the way of the operator. In Fig. 1 is shown a part of the table top separated from the main portion of the table top 10, which part is capable of being moved away from the main portion, all as well known. This enables the spreader or slitter to be turned down into operative position. In Fig. 1, the bolt 24 is below the table top 10 at all times being visible in Fig. 1, as also the member 17, because of the absence of the top, and due to the perspective drawing.

I wish it to be understood that I do not desire to be limited to the exact details of construction shown and described, for obvious modifications will occur to a person skilled in the art.

I claim:

1. In a circular saw wood cutting machine, the combination of a member having a slot secured to the frame of the machine, a crescent shaped spreader having its back portion engaging said slot, and a spring for pressing said spreader into said slot.

2. In a circular saw wood cutting machine, the combination of a member having a slot secured to the frame of the machine, a crescent shaped spreader having its back portion engaging said slot, a spring for pressing said spreader into said slot, a pivot bolt for one end of said spreader and for supporting said spring secured to the frame of the machine, said spring permitting the spreader to be disengaged from the slot and swung into inoperative position around said bolt.

3. In a circular saw wood cutting machine, the combination of a member having a slot secured to the frame of the machine, a crescent shaped spreader having its back portion engaging said slot, a spring for pressing said spreader into said

slot, a pivot bolt for one end of said spreader and for supporting said spring secured to the frame of the machine, said spring permitting the spreader to be disengaged from the slot and swung into inoperative position around said bolt, said spreader being bent into a sleeve surrounding said bolt.

4. In a circular saw wood cutting machine, the combination of a member having a slot secured to the frame of the machine, a crescent shaped spreader having its back portion engaging said slot, and a spring for pressing said spreader into said slot, said spreader having a part at right angles to the plane of the spreader, said part being bent to a sleeve shape.

5. In a circular saw wood cutting machine, the combination of a member having a slot secured to the frame of the machine, a crescent shaped spreader having its back portion engaging said slot, a spring for pressing said spreader into said slot, said spreader having a part at right angles to the plane of the spreader, said part being bent to a sleeve shape, and a bolt spaced from the slot the length of said part.

6. In a circular saw wood cutting machine, the combination of a member having a slot secured to the frame of the machine, a crescent shaped spreader having its back portion engaging said slot, a spring for pressing said spreader into said slot, said spreader having a part at right angles to the plane of the spreader, said part being bent to a sleeve shape, and a bolt spaced from the slot the length of said part, said spring acting on said sleeve and means on the bolt for adjusting the spring.

CHARLES GALANGA.
